UNITED STATES PATENT OFFICE.

JOHN E. KLINE, OF UNION CENTRE, ILLINOIS, ASSIGNOR OF ONE-HALF TO
WILLIAM F. REDMAN, JOHN GALBREATH, AND JOHN W. REDMAN, ALL
OF SAME PLACE.

CAR-COUPING.

SPECIFICATION forming part of Letters Patent No. 443,597, dated December 30, 1890.

Application filed August 23, 1890. Serial No. 362,813. (No model.)

To all whom it may concern:

Be it known that I, JOHN E. KLINE, a citizen of the United States, residing at Union Centre, in the county of Cumberland and State 5 of Illinois, have invented a new and useful Car-Coupling, of which the following is a specification.

This invention relates to car-couplings, and more especially to that class thereof known 10 as "draw-heads," the object of the invention being to provide a vertically-movable draw-head which will accommodate itself to other draw-heads of different heights, said draw-head containing coupling devices, all as herein 15 thereafter specifically described, and illustrated in the drawings, in which—

Figure 1 is a plan view of a portion of a draw-bar and the whole of the draw-head of my improved construction, showing a link as 20 locked therein. Fig. 2 is a longitudinal section of the same with the draw-head slightly raised above a horizontal line and the link-catch elevated. Fig. 3 is a perspective detail of the draw-head and its operating devices.

25 Referring to the said drawings, letter B designates a draw-bar, which is suitably supported beneath the car-body and has a deep recess R at its front end, and the letter H designates the draw-head of approximately the 30 same size in cross-section as the draw-bar and having a tongue T at its rear end, which fits loosely in said recess R. Keyed in the tongue T and journaled through the front end of the draw-bar B each side of said tongue is a horizontal 35 operating-shaft O, which extends to the right of the draw-head and has an operating-handle H' on its outer end, standing about opposite the side of the car. When this handle is moved, it will be obvious that 40 the draw-head will be raised and lowered, turning about the journals of the rod O in the draw-bar B.

In the front end of the draw-head is the usual hole for the reception of the link, which 45 hole is open in a slot S through the top of the draw-head. In this slot works a catch K, having a beveled front face, which catch is keyed to a coupling-shaft C, journaled through the sides of the draw-head, extending to the 50 right parallel with the operating-shaft O, and

having a weighted handle-lever W on its outer end. This lever is so arranged with reference to the catch K that when the latter is elevated, as shown in Fig. 2, the weight W will be thrown slightly forward of a vertical 55 line and will hold the catch so elevated. When the catch is in its operative position, its tip rests behind a shoulder Q in the bottom of the interior of the draw-head, as shown in Fig. 2, and in this position the weight W 60 tends to hold the catch in place. The operation of coupling by forcing the link into the draw-head, raising the catch thereby, and permitting it to automatically drop into the link, is well known in this class of devices 65 and needs no elaboration here.

With a draw-head of the above construction and embodying the coupling devices described, or, in fact, any other suitable coupling devices which may be used in this connection, a car can be coupled to another car whose draw-head is higher or lower without the use of the bent links heretofore necessary, which links were hard to find when most wanted, liable to become lost after they were 70 used, and at all times much weaker than an ordinary straight link and considerably more expensive to make. By operating the handle H' from the side of the car the draw-head H can be raised or lowered, so as to direct the 75 link into a higher or lower draw-head or so as to bring this draw-head into position to receive a link carried by the other car. The handle-lever W may be also operated from the side of the car to engage or disengage the 80 link from the draw-head; and my improved draw-head may be used with those of any other construction wherein a link is employed.

In some cases I may prefer to substitute for the handle H' a lever 1, having an eye 2 85 in its upper end, and a rod 3 is linked into said eye and at its other end linked to the short arm 4 of a handle-lever 5, mounted on a pivot 6 in the side of the car. This lever is maintained in proper position by a spring 7, 90 which normally supports the front end of the draw-head also in proper position, all as will be clearly understood.

What is claimed as new is—

1. In a car-coupling, the combination, with 100

the draw-bar B, having ears at its front end and a recess R between them, of the draw-head H, having a rearwardly-extending tongue T loosely seated in said recess, an operating-rod O, journaled through said ears and keyed in said tongue, an operating-handle H' on said rod at the side of the car, and coupling devices carried by said head, substantially as described.

10. 2. In a car-coupling, the combination, with the draw-bar B, the draw-head H, having a hole in its front end opening through a slot S in its top, said draw-head being pivotally connected to said draw-bar, and means, substantially as described, for raising and lowering the front end of the draw-head around its pivot, of the catch K in said slot, the coupling-shaft C, journaled through the draw-head and keyed in said catch, and a weighted handle-lever W on the outer end of said shaft, as and for the purpose set forth.

3. In a car-coupling, the combination of the draw-bar B, the draw-head hinged to the draw-bar, having the hole in its front end opening 25 through the slot S in its top and provided with the shoulder Q, the operating-rod O, journaled in the draw-bar and keyed to the draw-head, the coupling-shaft C, journaled

through said draw-head and extending to the side of the car, a catch K, keyed on said shaft 30 C and adapted to rest against said shoulder, and the weighted handle, substantially as described.

4. In a car-coupling, the combination, with the draw-bar B, having ears at its front end 35 and a recess R between them, the draw-head H, having a rearwardly-extending tongue T loosely seated in said recess, an operating-rod O, journaled through said ears and keyed in said tongue, and an operating-handle H' on 40 the outer end of said rod at one side of the draw-head, of the catch K within said draw-head, the coupling-shaft C, journaled through the draw-head and keyed in said catch, and a weighted handle-lever W on the outer end 45 of said shaft and at the same side of the draw-head as said operating-handle, as and for the purpose hereinbefore set forth.

In testimony that I claim the foregoing as my own I have hereto affixed my signature in 50 presence of two witnesses.

JOHN E. KLINE.

Witnesses:

AMOS HUGH LACEY,
JOHN L. LEVINGSTON.
